(57) **CLAIM**

The ornamental design for a lamp, as shown and described.

DESCRIPTION

This invention relates to an ornamental design for a lamp acting as a lighting fixture.

FIG. 1 is a top perspective view of a lamp in accordance with this invention;

FIG. 2 is an enlarged fragmentary side view thereof, with the lamp cover removed for clarity of disclosure and with the length reduced to fit on the page;

FIG. 3 is an enlarged fragmentary top plan view thereof, with the length reduced to fit on the page;

FIG. 4 is an enlarged top end perspective view thereof;

FIG. 5 is an enlarged end view thereof;

FIG. 6 is a bottom perspective view thereof; and,

FIG. 7 is a second bottom perspective thereof.

The broken lines in the drawings represent environmental structure and form no part of the claimed design.
